FISHING ROD CARRIER FOR AUTOMOBILES

Frank R. Burnett, Downey, Irvin E. Schmidke, South Gate, and George Pelletier, Wilmar, Calif.; said Pelletier assignor to said Burnett and Schmidke, jointly

Application August 3, 1951, Serial No. 16,138

Term of patent 14 years

(Cl. D14—6)

To all whom it may concern:

Be it known that we, Frank R. Burnett, Irvin E. Schmidke, and George Pelletier, all citizens of the United States, residing in Downey, South Gate, and Wilmar, respectively, county of Los Angeles, State of California, have invented a new, original, and ornamental Design for Fishing Rod Carrier for Automobiles, of which the following is a specification, reference being had to the accompanying drawing, forming part thereof.

Figure 1 is a perspective view of a fishing rod carrier for automobiles, embodying our novel design;

Figure 2 is a plan view thereof;

Figure 3 is a side view; and

Figure 4 is a sectional view taken as on a line 4—4 of Figure 3.

The dotted line showing of the ties is for illustrative purposes only.

We claim:

The ornamental design for a fishing rod carrier for automobiles, substantially as shown and described.

FRANK R. BURNETT.
IRVIN E. SCHMIDKE.
GEORGE PELLETIER.
